UNITED STATES PATENT OFFICE

HEZEKIAH NAYLOR, OF PEKIN, ILLINOIS.

IMPROVED CASTER FOR FURNITURE.

Specification forming part of Letters Patent No. **58,879**, dated October 16, 1866.

To all whom it may concern:

Be it known that I, HEZEKIAH NAYLOR, of Pekin, in the county of Tazewell and State of Illinois, have invented a new and useful Improvement in Caster-Wheels for Furniture; and I do hereby declare that the following is a full, clear, and exact description of the mode of constructing the same, reference being had to the annexed drawings, making part of this specification, in which—

Figure 1 is a perspective view. Fig. 2 is a perspective view of the friction-balls; Fig. 3, a view of the bottom; Fig. 4, partly a side elevation and partly a section.

The same letters are employed in describing the same parts.

A represents the base of the caster or leg of the article of furniture, in which there is a chamber sufficient to receive the caster-ball B and friction-balls C. The caster-ball B protrudes through a circular opening in the base of less diameter than the ball. The caster-ball B rests against three friction-balls, C, which are placed at the angles of an equilateral triangle, so as to revolve freely in their respective cavities, turning upon journals D, which sustain the weight of the article to

which the caster is attached, by which means the friction of the caster-ball B in rolling is divided among the several journals, and the difficulty of moving the article to which the caster is attached greatly lessened.

I do not claim the use of a caster-ball, B, for that I know is not new; nor do I claim such a ball when supported upon friction-wheels, for I am aware that various arrangements for this purpose have been made; but

What I do claim as my invention, and desire to secure by Letters Patent, is—

A caster in which the caster-ball B turns on three friction-balls, C, which are placed in the angles of an equilateral triangle turning on journals which have bearings on both sides of said balls in recesses formed for the purpose in the top of the caster, substantially as described.

In testimony whereof I have signed my name to this specification in the presence of two subscribing witnesses.

HEZEKIAH NAYLOR.
